UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ILLUMINATING DEVICE.

1,355,300.

Specification of Letters Patent. Patented Oct. 12, 1920.

Application filed January 27, 1916. Serial No. 74,583.

To all whom it may concern:

Be it known that I, REUBEN B. BENJAMIN, a citizen of the United States, residing at Chicago, in the county of Cook and State 5 of Illinois, have invented new and useful Improvements in Illuminating Devices, of which the following is a full, clear, concise, and exact description, reference being had to the accompanying drawing, forming a 10 part of this specification.

My invention relates to illuminating devices and more specifically to such devices provided with a concave reflector, and a receptacle for an electric lamp adjustable 15 to bring the lamp in proper position with respect to the reflector.

Among the objects of my invention is to provide such a device which will be simple in construction and efficient in use.

20 In the drawings, in which I have shown an embodiment of my invention—

Figure 1 is a vertical axial section of a lamp embodying my invention, the section being taken on the line 1—1 of Fig. 2; and

25 Fig. 2 is a section on the line 2—2 of Fig. 1.

Referring now to the drawings in detail I have shown my invention in connection with a lamp comprising a casing 10, a reflector 11 within the casing, a receptacle 12 also supported within the casing, a frame 13 pivoted with respect to the casing 10, and a front glass 14 mounted in the frame 13.

The casing 10 is provided with an opening 15 in the rear of the receptacle 12 through which the adjusting means for the receptacle extend. The reflector 11 has an opening 16 in its rear portion through which the receptacle 12 extends and in 30 which it is slidably and tiltably supported, and is provided with a plurality of smaller openings 17 (three in number as shown) in which the pins, which prevent rotation of the receptacle 12, slide.

45 The receptacle 12 comprises an insulating support or base 18, a center contact 19 secured to the base by means of an eyelet 20, and a shell or socket 21 of conducting material slidable and tilttable in the opening 16.

50 The means for tiltably and slidably adjusting the receptacle 12 comprise a screw 23 rigidly secured to the plate 24 which in turn is rigidly secured to the base 18, a nut 25 having a flange portion 25a engaging the

inner surface of the casing 10, an operating portion 26 extending outside of the casing 10, and a lock nut 27 threaded on the nut 26. The plate 24 is secured to the base 18 by means of a plurality of eyelets 28 in which eyelets are secured split pins 29 which slide 55 in the openings 17 in the reflector 11. A lamp 30 is detachably secured in the socket 21 in any suitable manner, the center contact 31 of the lamp engaging the center contact 19 and the shell contact 32 of the lamp 60 engaging shell or socket 21. A flange or sleeve 33 may be formed about the opening 16 to afford a bearing for the socket 21, and flanges or sleeves 34 may be formed around the opening 17 to afford bearings 65 for the pins 29.

In the form I have illustrated one of the terminals is grounded, the circuit being from the center contact 19, through the lamp circuit to the shell contact 32, to the 70 grounded shell or socket 21.

In case it is desired to adjust the lamp 30 with respect to the reflector 11 the lock nut 27 is loosened after which the socket can be tilted in any direction about the flange 33 80 as a support, the opening 15 in the casing 10 being large enough to permit movement of the nut 25 in any direction. If it is desired to adjust the lamp 30 axially, the nut 25 is turned in one direction or the other 85 forcing the lamp 30 in or out as desired. After the desired adjustment of the lamp is secured the lock nut 27 is again tightened up.

The split pins 29 will prevent rotation of 90 the receptacle 12 when the lamp is being inserted in the socket 21 and when the nut 25 is being turned.

Having thus described my invention what I claim as new and desire to secure by Letters Patent is:—

1. In a device of the class described, a concave reflector, a housing therefor having an opening therein, an electric lamp receptacle, means for supporting said receptacle 100 to tilt in any direction and to move axially with respect to said reflector, means for manually tilting said receptacle in any direction comprising a member secured to said receptacle and extending through and movable in said opening, and means for securing said member in any adjusted position comprising two clamping members for en-

- gaging said housing adjacent the edge of said opening, one of said clamping members serving as a means to move said receptacle axially.
5. 2. In a device of the class described, a concave reflector, a housing therefor having an opening therein, an electric lamp receptacle, means for supporting said receptacle to tilt in any direction and to move axially with respect to said reflector, means for manually tilting said receptacle in any direction comprising a member secured to said receptacle and extending through and movable in said opening, and means for securing said member in any adjusted position comprising two clamping members having interengaging screw threads for engaging said housing adjacent the edge of said opening, one of said clamping members serving as a means to move said receptacle axially.
10. 3. In a device of the class described, a concave reflector having a circular opening therein, and an electric lamp receptacle extending through said opening mounted to tilt in any direction about the edge of said opening as a fulcrum.
15. 4. In a device of the class described, a concave reflector having a circular opening therein, and an electric lamp receptacle extending through said opening mounted to tilt in any direction about the edge of said opening as a fulcrum and to slide on said edge as a support.

In witness wherof, I have hereunto subscribed my name.

REUBEN B. BENJAMIN.
